ELECTRODE SEALING-IN

George A. Freeman, East Orange, N. J., assignor
to Westinghouse Electric & Manufacturing
Company, East Pittsburgh, Pa., a corporation
of Pennsylvania

Application November 25, 1938, Serial No. 242,178

2 Claims. (Cl. 176—7)

My invention relates to electrodes and especially to the sealing in of such electrodes in lamps requiring application of high temperatures.

An object of my invention is to prevent the 5 oxidization of electrodes while they are being sealed in the casing.

Other objects and advantages of the invention will be apparent from the following description and drawing, in which:

10 Fig. 1 is an elevation of a lathe in which my invention has been incorporated.

Fig. 2 is an enlarged cross-sectional view of the pressure release mechanism of Fig. 1.

15 Fig. 3 is a view mainly in cross section of the chuck, and lamp apparatus illustrating one of the first steps in the formation of a quartz lamp according to my invention.

20 Figs. 4 and 5 are views mainly in cross-section of the tube and adjacent jaws of the chucks illustrating the formation of one end of the seal 20 of the lamp.

25 Fig. 6 is a view mainly in cross section of the lamp and adjacent jaws of the chucks illustrating the method of forming the seal about the other end of the quartz lamp.

Fig. 7 is a view in elevation of the completed lamp.

30 Certain types of lamps and discharge devices require a very high temperature for the sealing-in of the electrodes. This is especially true when the container is of certain materials such as that of quartz. If the electrodes were sealed in a quartz tube in air, the high temperature adjacent to the electrode renders them worthless 35 in view of the resulting oxidization. Pure nitrogen has been utilized as an atmosphere in which to seal-in the tubes but methods heretofore utilized have not satisfactorily applied the nitrogen atmosphere to the lamp. It is necessary, of course, that the nitrogen not interfere with the application of the flame and the heat therefrom to the outside of the casing. It is further important that the nitrogen be regulated so that it has the desired low pressure within the tube while

40 the seal is being formed and then increased pressure when the seal has been sufficiently formed to stand such pressure. The difficulty with prior art methods has been that the pressure of the nitrogen has been so low in the early 45 steps of the sealing-in process that air has been sucked into the lamp through the opening being sealed and has defeated the purpose of the nitrogen atmosphere. My invention removes this difficulty by providing a sufficient atmosphere of 50 nitrogen to the interior of the tube during the

sealing off process and an increased pressure during the final steps of the seal.

In Fig. 1, I have illustrated a lathe 10 with revolving chuck 11 as illustrated holding a tube 12 therein and a longitudinal moving chuck 13 holding an electrode assembly 14 which is to be inserted in the tube 12 and sealed thereto by means of the flame 15.

A tube 16 leads from a nitrogen supply to a pressure release 17 illustrated in enlarged view 10 Fig. 2. This pressure release has a side opening 18 from its tubular connection 19 with the tube 16. Around this side opening 18 is a tube 20 which may be of rubber or metal, although compressible material is preferred, having axial 15 opening 21 therethrough that is of smaller diameter than the tube connection to the lamp chuck. A tube 22 leads from the three-way connection of 19 to the jaws 11 of the chuck as illustrated in full and dotted lines in Fig. 1. The tube 20 20 must have sufficient length to slow up the escaping gas in order to prevent lowering the pressure in the tubing connected to the pressure release chamber. If this flow is fast, as it would be without tube 20 being used, a partial vacuum will be 25 created in tube 22. By impeding the flow through tube 19 by the use of tube 20 of suitable small cross-section and of sufficient length, the pressure in tube 22 is maintained high enough to insure gas flow toward the lamp chuck and 30 not from it. As an example, I have found that with rubber tubing 20 having an opening of approximately the same diameter as the tubing 16 and 22, for example $\frac{1}{8}$ inch, then a length of four to six or more inches of tubing 20 will work 35 satisfactorily. This length can be shortened if the diameter of the opening 21 is made smaller. The pressure of the gas and length and diameter of opening of the release tube 20 is such as to produce an atmosphere slightly greater than the 40 outside atmosphere.

As illustrated in Fig. 3, the tube 22 terminates at a central chamber 23 of the chuck which has a central opening 24 to the central point of the chuck. For the purpose of sealing-in the special 45 type of tube which necessitated my invention, I also provide a side opening 25 from the central chamber 23 and this side opening terminates in a flexible tubular member 26 which may take the form of a small rubber hose that can be closed 50 off when not desired as by the clamp 27 holding it against the side of the chuck.

In order to illustrate the application in the invention, I have chosen a tube which is rather difficult to seal by reason of its small structure 55

and the high temperature which must be applied to each end for the purpose of sealing the electrodes therein. The complete tube, except for the closing of the tubulation 29, is illustrated in Fig. 7. This tube comprises a hollow tubular container 30 of rather small diameter quartz which is illustrated approximately actual size. This container has a single lead-in electrode 31 at one end and a double lead-in electrode 32 at the opposite end. Both the electrodes 31 and 32 must be sealed in the tube under the high temperature necessary to make a seal with the quartz tubing 30 and have about these electrodes a continuous but varying pressure of nitrogen or other inert gas to form the seal without any oxidization of the electrode structure that would render them worthless.

Returning to Fig. 3, I have disclosed the tube 38 having one of its open ends 33 surrounding the opening 24 supplying nitrogen from the central portion of the chuck. The other chuck has the electrode 14 secured therein and this electrode is moved within the end 34 of the tube until the bead of glass 35 about the electrode lead-in is adjacent the tip end 34 of the tube as illustrated in dotted lines. The tubulation 29 is closed in this instance. The supply from the nitrogen source is in operation and in view of the restricted side opening 21 in the pressure release 17, the nitrogen is applied to the interior of the tube with just sufficient pressure to keep a steady stream flowing past the electrode 14 through the open end 34 to prevent any egress of air therein and thus prevent any oxidization of the electrode. This pressure is also gentle enough to permit the gradual closing of the seal as disclosed in Figs. 3 and 4. When the seal has been closed, the operator applies his finger as disclosed in dotted lines at 36 in Figs. 1 and 2, so that the pressure of the nitrogen inside of the tube increases as disclosed by the heavier arrows 38 in Fig. 5 to round out the seal as it cools at 39.

The end of the tubulation 29 is then opened at 40 and the tube reversed with its sealed end 45 within the revolving jaws 11 as illustrated in Fig. 6. The side opening 25 and the rubber hose connection 36 to the central chamber 23 of the chuck is then connected to the tubulation 29 to provide the entrance of the nitrogen into the interior of the tube. The longitudinally moving chuck 13 then has the tube terminal cathode electrode structure 32 with its bead 41 inserted in the remaining open end 33. The nitrogen then flows

through the tube and out the open end 33 at a gentle pressure until the seal is closed. The pressure is then increased by the operator applying his finger to the restricted opening 21 and the seal rounded out as the seal cools. The quartz casing tube is then in the form disclosed in Fig. 7 ready for the usual treatment and gas filling and sealing off of the tubulation 29.

It will be noted that by the above apparatus and these steps outlined, I have accomplished the sealing of a single and a double end electrode in opposite ends of a tube of quartz glass without any danger of the electrodes being oxidized. The pressure of the inert gas is at all times under the accurate control of the operator. An experienced operator can, of course, by the length of time and the period of closing the restricted side opening 21, control the inert atmosphere to a pressure desired at any particular instance.

I have chosen the particular tube and materials described in order to emphasize the application of my invention to a tube which is difficult to satisfactorily seal. It is apparent, however, that the invention is applicable to various other types of tubes and that various modifications may be made in the particular form or apparatus illustrated and the steps described. Accordingly, I desire only such limitations to be imposed upon the following claims as is necessitated by the prior art.

I claim:

1. Means for sealing a tube comprising a chuck, a gas connection to the central portion within the jaws of said chuck having an open side release with greater impedance to gas flow than said gas connection.
2. The method of sealing an electrode in one end of a glass tube which comprises revolving said tube, applying an inert atmosphere to the interior of the tube while revolving, releasing the inert atmosphere only to the extent that the pressure applied to the interior of the tube does not interfere with the sealing process and yet is sufficient to prevent any outside atmosphere entering the tube, inserting an electrode in the inert atmosphere flowing from the open end of the tube, applying heat thereto and sealing the end of the tube about said electrode, and stopping the release of said inert atmosphere while the seal is still molten to round out the tube around the electrode.

GEORGE A. FREEMAN.
